MOTOR SHROUD FOR ELECTRIC MOWER

Alexander B. Musichuk, Parma, Ohio, assignor to MTD
Products Inc., a corporation of Ohio

Filed June 5, 1969, Ser. No. 17,524

Term of patent 14 years

Int. Cl. D8—01

U.S. Cl. D40—1

FIG. 1 is a perspective view of a motor shroud embodying my design;

FIG. 2 is one side view of the same;

FIG. 3 is an opposite side view of the same;

FIG. 4 is a top plan view of the same;

FIG. 5 is a bottom plan view of the same;

FIG. 6 is one end view of the same; and

FIG. 7 is an opposite end view of the same.

I claim:

The ornamental design for a motor shroud for electric mower, substantially as shown.
